(57) **CLAIM**

The ornamental design for a set of automotive display props, as shown and described.

DESCRIPTION

FIG. 1 is an environmental view of a set of automotive display props used to prop open a driver side door, a trunk lid, and a passenger side door of an automotive vehicle, in accordance with an embodiment of this disclosure;

FIG. 2 is a perspective view of a driver side door automotive display prop of the set of automotive display props of FIG. 1;

FIG. 3 is a front end view of the driver side door automotive display prop of the set of automotive display props of FIG. 1;

FIG. 4 is a left side view of the driver side door automotive display prop of the set of automotive display props of FIG. 1;

FIG. 5 is a rear end view of the driver side door automotive display prop of the set of automotive display props of FIG. 1;

FIG. 6 is a right side view of the driver side door automotive display prop of the set of automotive display props of FIG. 1;

FIG. 7 is a top view of the driver side door automotive display prop of the set of automotive display props of FIG. 1;

FIG. 8 is a bottom view of the driver side door automotive display prop of the set of automotive display props of FIG. 1;

FIG. 9 is a perspective view of a trunk lid automotive display prop of the set of automotive display props of FIG. 1;

FIG. 10 is a front end view of the trunk lid automotive display prop of the set of automotive display props of FIG. 1;

FIG. 11 is a left side view of the trunk lid automotive display prop of the set of automotive display props of FIG. 1;

FIG. 12 is a rear end view of the trunk lid automotive display prop of the set of automotive display props of FIG. 1;

FIG. 13 is a right side view of the trunk lid automotive display prop of the set of automotive display props of FIG. 1;

(Continued)

FIG. 14 is a top view of the trunk lid automotive display prop of the set of automotive display props of FIG. 1; FIG. 15 is a bottom view of the trunk lid automotive display prop of the set of automotive display props of FIG. 1; FIG. 16 is a perspective view of a passenger side door automotive display prop of the set of automotive display props of FIG. 1; FIG. 17 is a front end view of the passenger side door automotive display prop of the set of automotive display props of FIG. 1; FIG. 18 is a left side view of the passenger side door automotive display prop of the set of automotive display props of FIG. 1; FIG. 19 is a rear end view of the passenger side door automotive display prop of the set of automotive display props of FIG. 1; FIG. 20 is a right side view of the passenger side door automotive display prop of the set of automotive display props of FIG. 1; FIG. 21 is a top view of the passenger side door automotive display prop of the set of automotive display props of FIG. 1; and, FIG. 22 is a bottom view of the passenger side door automotive display prop of the set of automotive display props of FIG. 1. Broken lines in the Drawings are used to illustrate portions of the article of manufacture or portions of its environment that form no part of the claimed design.

1 Claim, 10 Drawing Sheets
